STAIRWAY

Raymond J. Fick, North Tonawanda, N. Y.

Application September 29, 1942, Serial No. 460,052

8 Claims. (Cl. 228—50)

This invention relates to ladders or stairways of the so-called disappearing type.

Ladders and staircases of the general class in which the present invention falls are arranged, in various ways, to be stored in an upper position. Where the ladder or stairway is designed to permit passage from one floor of a building to another the stairway or ladder is frequently arranged to be housed or stored above the upper floor when it is not in use. While the principles of the present invention have varying application, and while either a stairway or a ladder may be constructed according to the principles of the present invention without departing therefrom, a specific embodiment of the invention will be described in the ladder form and reference will be had to a familiar instance of use of devices of this kind, namely to give access to the attic or garret of a building where it is not desired that the ladder or stairway be in position for use at all times. This latter is for the reason that the space occupied by the ladder when it is in use serves other purposes when the ladder is not being used.

The present invention is characterized by extreme simplicity of construction which enables its production on a very inexpensive basis and accordingly places the device within practical reach of all who have use for such means of ascension. Where no installation of this kind is afforded and a hatchway is provided between a room of a building and an attic or a garret thereabove, a common stepladder is frequently employed. The inconvenience of bringing a step-ladder or other portable ladder or stairway to the point of desired use and subsequently removing it, together with the inherent danger of entering or leaving an attic by use of a step ladder, are believed to be obvious.

According to the present invention a simple two-section ladder is provided with a third section which functions to move the two ladder sections proper between their desired operative and stored positions. The third section performs the function of guiding the upper end of the upper of the two ladder sections in a predetermined arcuate path during movement to or from operative position so that such upper section may be conveniently projected through a hatchway of minimum compass and so that its upper end is stored in desired position with respect to the other elements. It has been stated above that the extreme simplicity of the arrangement is an important advantage. A further important object is attained in so arranging the ladder sec-

tions that they may be stored in a space of very small compass. The proposed arrangement is further marked by the fact that the device may be moved to and from operative position through a hatchway or other opening of extremely small size, as was pointed out above. In fact, any opening of sufficient size to permit a user to pass upwardly therethrough is more than adequate.

In the exemplary form illustrated, I have shown my novel ladder arrangement in conjunction with a hatch cover or door, the two being so associated as to have common control means whereby opening of the door and movement of the ladder to usable position may be simply effected. Subsequent movement of the ladder to stored position and closure of the door is likewise extremely simple. The common control means are arranged to retain both the ladder and the door in predetermined desired positions against gravitational forces.

In the accompanying drawing:

Fig. 1 is a fragmentary cross-sectional view of a building showing one form of the ladder arrangement of my invention in side elevation; and,

Fig. 2 is a fragmentary elevational view of the mid portion of the two section ladder of Fig. 1 viewed at right angles to Fig. 1 and with the ladder sections in extended position, that is, in position for use.

In the drawing like characters of reference denote like parts and in Fig. 1 the numeral 5 designates a building structure having a lower floor 6, an upper floor 7 and a roof or further upper floor 8. The upper floor 7 has therein a hatchway 9 to give egress to the upper floor from the lower. Numerals 10 and 11 designate respectively upper and lower ladder sections which are pivotally connected by a common rung 12. In Fig. 1 the full line representation shows the ladder in stored condition with a hatch door 13 in closed position. The dot-and-dash line position designated "A" is the position of use, while the dot-and-dash line position designated "B" is an intermediate position which the ladder sections occupy during movement of the ladder from stored to usable position and vice versa.

Arm means are provided for guiding the upper end of the upper ladder section 10 and in the illustrated instance the arm means comprises a third ladder section 14 which has a rung 15 at one end which is a common rung of the ladder sections 10 and 14 and comprises a pivotal connection therebetween. A rung 16 at the other end

of the ladder section 14 is pivotally attached to the floor 7 by means of bearing blocks 17.

The lower ends of the lower ladder section 11 are chamfered as at 18 and in the stored position shown in full lines in Fig. 1 the chamfers rest on the edge of the hatchway 9 and the condition of the ladder sections in this position is unstable. The full line position is maintained, as long as desired, by means of a cable, cord or the like, designated 20 and extending from engagement with the pivot run 12 over a pair of spaced pulleys 21 and 22 attached to the roof or ceiling 8 and downward to a hook 23 secured to a wall 24 of the building. At this point the cord 20 is fitted with a ring 25 which may be engaged over the hook 23.

An extension 26 of the cord 20 reaches about a second pair of pulleys 27 and 28, likewise secured to the roof or ceiling 8, and terminates in engagement with an edge of the closure 13 which is opposite its hinged connection in the hatchway 9. It will be noted that the extension 26 of the cord 20 is likewise provided with a ring 30. When it is desired to use the ladder means, a user will pull downwardly on the cord 26 until the door moves to the position shown in dot-and-dash lines in Fig. 1. At this time the ring 30 is substantially in registry with the hook 23 and the operator may remove the ring 25 from the hook 23 and substitute the ring 30.

Release of the ring 25 from the hook 23 and paying the cord 20 out upwardly will result in downward movement of the lower ladder section 11 through the hatchway 9 to the position indicated in dot-and-dash lines at "B." The weight of this depending ladder section will continue the downward movement thereof and the upper ladder section 11 will likewise be moved through the hatchway 13. During the latter phase of the operation the upper end of the ladder section 10, that is, the end which is uppermost when the ladder is in use, is constrained to arcuate movement with the outer end of the arm means, the third ladder section 14. In this way the upper ladder section 10 is disposed in positions which facilitate its projection through the hatchway 9.

It will be noted that natural gravitation of the lower ladder section to the floor 6 will leave it in an approximately vertical condition and withdrawal to the position shown in dot-and-dash lines at "A" is effected by the user. In movement to the position designated "A," portions 32 of the ladder 10 which project beyond the pivot rung 12 engage in channel clips 34 carried by the ladder section 11 at opposite sides thereof, see Fig. 2. By reason of the presence of the clips 34 and the engagement of the projecting ladder portions 32 therein, the ladder sections 10 and 11 present a rigid unitary composite ladder in the position designated "A" in Fig. 1. Provision of the arm means 14 in the form of a third ladder section facilitates emergence into the space above the floor 7 by a user of the device. The three rungs of this section provide convenient grasping means to complete ascension of the upper ladder section 10.

Movement of the ladder to stored position and subsequent closure of the door 13 of the hatchway are obviously effected by merely reversing the hatch door opening and ladder projecting procedure heretofore outlined. While a single complete embodiment of the principles of my invention is set forth herein by way of example, it is to be understood that the spirit and scope of the

invention is not limited thereto or otherwise than as defined in the appended claims.

I claim:

1. Stairway construction for use with a building floor having a hatchway therein, said construction comprising means pivotally attached to said floor adjacent said hatchway and having an end portion movable pivotally between positions above said hatchway and spaced therefrom, a pair of stairway sections pivotally connected in end-to-end relation and one of them having its outer end pivotally connected to the end portion of the arm means whereby said pair of sections depend therefrom through said hatchway when said end portion is above said hatchway, and means for simultaneously raising the pivotal connection between said sections through said hatchway and above said floor and pivoting said arm means to dispose its end portion in position spaced from said hatchway to dispose said sections in inverted V position.

2. Stairway construction for use with a building floor having a hatchway therein, said construction comprising means pivotally attached to said floor adjacent said hatchway and having an end portion movable pivotally between positions above said hatchway and spaced therefrom, a pair of stairway sections pivotally connected in end-to-end relation and one of them having its outer end pivotally connected to the end portion of the arm means to depend therefrom through said hatchway when said end portion is above said hatchway, and means engaging said stairway sections adjacent their pivoted connection for simultaneously raising the pivotal connection through said hatchway and pivoting said arm means to dispose its end portion in position spaced from said hatchway to dispose said sections in inverted V position.

3. Stairway construction for use with a building floor having a hatchway therein, said construction comprising means pivotally attached to said floor adjacent said hatchway and having an end portion movable pivotally between positions above said hatchway and spaced therefrom, a pair of stairway sections pivotally connected in end-to-end relation and one of them having its outer end pivotally connected to the end portion of the arm means to depend therefrom through said hatchway when said end portion is above said hatchway, and means for exerting an upward force against the pivotal connection between said sections for raising said connection through said hatchway and substantially above said floor and simultaneously pivoting said arm means to dispose its end portion in position spaced from said hatchway to dispose said sections in inverted V position.

4. Stairway construction for use with a building floor having a hatchway therein, said construction comprising means pivotally attached to said floor adjacent said hatchway and having an end portion movable pivotally between positions above said hatchway and spaced therefrom, a pair of stairway sections pivotally connected in end-to-end relation and one of them having its outer end pivotally connected to the end portion of the arm means to depend therefrom through said hatchway when said end portion is above said hatchway, and means for simultaneously raising the pivotal connection between said sections through said hatchway and pivoting said arm means to dispose its end portion in position spaced from said hatchway to dispose said sections in inverted V position, said means com-

prising pulley means substantially above said floor and cable means extending upwardly from said ladder sections through said pulley thence downwardly to an accessible point below said floor.

5. Stairway construction for use with a building floor having a hatchway therein, said construction comprising means pivotally attached to said floor adjacent said hatchway and having an end portion movable pivotally between positions above said hatchway and spaced therefrom, a pair of stairway sections pivotally connected in end-to-end relation and one of them having its outer end pivotally connected to the end portion of the arm means to depend therefrom through said hatchway when said end portion is above said hatchway, and means for raising said sections through said hatchway and pivoting said arm means to dispose its end portion in position spaced from said hatchway to dispose said sections in inverted V position, said means comprising pulley means substantially above said floor and cable means extending upwardly from said ladder sections through said pulley thence downwardly to an accessible point below said floor, a cover for said hatchway hinged for upward opening movement, and second pulley means above said floor, said cable means having a continuous extension from the point below said floor to said second pulley means and downwardly for engagement with said door spaced from its hinged connection, and means below said floor for securing said cable means in various positions, whereby said cable means raises said stairway sections to stored position or opens said hatchway door for lowering of aid stairway sections upon movement in opposite directions of said cable means.

6. Stairway construction for use with a building floor having a hatchway therein, said construction comprising three ladder sections pivotally connected in end-to-end relation, the free end of one section being adapted to be pivotally attached to said building floor at a point spaced from said hatchway and in such position that its opposite end which is pivotally connected to the middle one of the three sections may be

swung from a position over said hatchway where the other two sections depend therethrough for use in gaining access to said building floor to an opposite position where said opposite end of the floor-attached section and the end of the middle section which is pivotally attached thereto are relatively remote from said hatchway, and means for disposing said middle section and the third section in inverted V position.

- 10 7. A disappearing stairway for gaining access to an upper floor through a hatchway therein, said stairway comprising in position for use upper and lower sections pivotally connected in end-to-end relation, arm means adapted to be secured to said upper floor for pivotal movement and having a free end portion pivotally engaging the upper end of said upper section whereby to guide the engaged end of said upper section to a position spaced horizontally from said hatchway upon upward movement of said upper and lower sections, and lifting means engaging said upper and lower sections medially for raising their pivotal connection to a point above said upper floor whereby the stairway is stored thereon in inverted V position offset from said hatchway.
- 15 8. A disappearing stairway for gaining access to an upper floor through a hatchway therein, said stairway comprising in position for use upper and lower sections pivotally connected in end-to-end relation, arm means adapted to be secured to said upper floor for pivotal movement having a free end portion pivotally engaging the upper end of said upper section whereby to guide the engaged end of said upper section to a position spaced horizontally from said hatchway upon upward movement of said upper and lower sections, pulley means above said upper floor, and cable means engaging said upper and lower sections medially and extending over said pulley means thence downwardly to a conveniently accessible point below said upper floor for manually raising the pivotal connection between the sections to a point above said upper floor whereby the stairway is stored thereon in inverted V position offset from said hatchway.
